UNITED STATES PATENT OFFICE.

WILLIAM R. YOUNG, OF NASHVILLE, TENNESSEE.

LICENSE-NUMBER-PLATE HOLDER.

1,386,751.

Specification of Letters Patent. Patented Aug. 9, 1921.

Application filed May 4, 1921. Serial No. 466,717.

To all whom it may concern:

Be it known that I, WILLIAM R. YOUNG, a citizen of the United States, residing at Nashville, in the county of Davidson and State of Tennessee, have invented certain new and useful Improvements in License-Number-Plate Holders, of which the following is a specification, reference being had to the accompanying drawings.

10 The purpose of the present invention is to provide a very simple and efficient holder for the license number plate of an automobile, whereby the plate may be supported detachably in position, and in such wise that 15 by removing the top flange of the holder, the number plate may be withdrawn.

Another purpose is the provision of a main or base plate provided with a marginal overlying flange on its bottom and end edges 20 and positioned rearwardly, between which and the body of the plate the number plate may be inserted, there being a removable top flange or strip straddling the upper edge of the base or main plate and having tongues 25 engaging under transversely disposed straps struck up from the base plate, to hold the top flange in position.

Another purpose is to provide a holder of this general character and for the purpose indicated, which may be manufactured 30 for a relatively low cost and sold for a reasonable profit, and adapted to hold the license number plate, so that it cannot be jarred or displaced owing to the vibrations 35 of the machine, the struck up straps likewise acting to prevent the top flange from being displaced by the vibrations of the machine.

While the design and construction at present illustrated and set forth is deemed preferable, it is obvious that as a result of a reduction of the invention to a more practical form for commercial purposes, the invention may be susceptible of changes, and the right to these changes is claimed, provided they 45 are comprehended within the scope of what is claimed.

The invention comprises further features and combination of parts, as will be herein-after set forth, shown in the drawings and 50 claimed.

In the drawings:—

Figure 1 is a view in elevation of the license number plate holder, showing the number plate in position therein, and showing 55 the slits (which cause the transverse straps to be formed) in dotted lines.

Fig. 2 is a view in elevation of the holder with the number plate removed.

Fig. 3 is a view in elevation of the reverse face of the holder.

Fig. 4 is a sectional view on line 4—4 of Fig. 3.

Fig. 5 is a longitudinal sectional view on line 5—5 of Fig. 3.

Referring to the drawings, 1 designates the main plate of the holder, which is provided with a marginal flange 2 on its bottom and end edges. The license number plate is designed to slide in position between the marginal flange and the face of the main plate, by inserting the number plate in position at the top. The main plate is provided with elongated slots 3 adjacent its upper edge and near the ends. The marginal portions of these slots 3 are disposed as shown clearly in Fig. 4, so as to countersink the heads of the screws 4, which fasten the main plate in position on the automobile. In fact the holder may be fastened at any suitable location, either on the chassis, 80 or on the body, or any other suitable place. The reason for countersinking the heads of the screws, is to permit the license number plate to be inserted in position, without being interrupted.

The plate 1 is provided with longitudinally extending slits 5 arranged in pairs, thereby causing straps 6 extending longitudinally of the plate to be formed. In fact these straps are struck out from one face of the plate, in order to permit of the passage of suitable means for holding a top flange on the main plate. In order to hold the license number plate in engagement with the marginal flange of the main plate, a removable flange or top 7 straddles the plate 1, and has a flange portion 8 overlying the number plate, which insures holding it from being displaced incident to the vibrations of the automobile. The top 7 has a flange portion 9 overlying the rear of the plate 1, and extending from said flange 9 are tongues 10, which engage between the straps 6 and one face of the plate 1. These tongues 10, frictionally engage in position between the straps 6 and the plate, and in such wise as to prevent displacement of the top or flange 7 incident to the vibrations of the machine. In fact the end portions 11 of the tongues are slightly bent, to prevent the tongues from working upwardly and thereby disengaging from under the straps. The mar-

ginal flange 2 of the plate 1 is formed integral with the plate, and is formed on the lower and end edges. In fact this flange 2 comprises the three sections, the lower section and the end sections, and when these sections are folded or bent to overlie the face of the plate 1, the mitered ends 12 conform and engage with each other. The overlying flange of the top 8 also has its ends mitered as shown at 13 to conform and engage with the mitered ends 14 of the end parts of the marginal flange 2.

In order to mount a license number plate in position, the top 7 is first removed, the number plate is then inserted between the flange 2 and one face of the plate 1, after which the top 7 is replaced, so as to straddle the number and main plate, the former of which is designated by the numeral 15. When the top 7 is moved into position, the tongues 10 engage frictionally between the straps 6 and the main plate.

The invention having been set forth, what is claimed as being useful is:

25. 1. In a device of the character and for the

purpose indicated, a holder plate provided with means on its lower and end edges for the reception of a license number plate, straps struck up from the holder plate, a top straddling the holder and number plates at their upper edges and having extensions frictionally engaging between the straps and the holder plate to retain the top in position.

2. In a device of the character and for the purpose indicated, a holder plate having means on its lower and end edges for the reception of a license number plate and provided with slots for the reception of fastening means to secure the holder plate to the automobile, a holder plate having struck up horizontal straps, a top straddling the holder and number plates at their upper edges and provided with tongues engaging between the straps and the holder plate 45 frictionally to hold the top in place.

In testimony whereof I hereunto affix my signature.

WILLIAM R. YOUNG.
